CLAIM

We claim the ornamental design for a shower facpelate for shower device, as shown and described.

DESCRIPTION

FIG. 1 is a front perspective view of a faceplate for a shower device, such as a showerhead or a hand shower.

FIG. 2 is a rear perspective view of the faceplate shown in FIG. 1.

FIG. 3 is a front view of the faceplate shown in FIG. 1.

FIG. 4 is a rear view of the faceplate shown in FIG. 1.

FIG. 5 is a right side view of the faceplate shown in FIG. 1, the left side view being substantially a mirror image thereof.

FIG. 6 is a top view of the faceplate shown in FIG. 1.

FIG. 7 is a bottom view of the faceplate shown in FIG. 1; and,

FIG. 8 is a rear perspective cross-sectional view of the faceplate shown in FIG. 1 to illustrate contours of the faceplate.

1 Claim, 7 Drawing Sheets
